(57) **CLAIM**

The ornamental design for a cutting tool, as shown and described.

DESCRIPTION

FIG. 1 is a front view of a cutting tool in accordance with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is an enlarged view of portion 8 of FIG. 1;

FIG. 9 is an enlarged view of portion 9 of FIG. 3;

FIG. 10 is an enlarged view of portion 10 of FIG. 5; and,

FIG. 11 is an enlarged view of portion 11 of FIG. 7.

The broken lines shown in the drawings represent portions of the cutting tool that form no part of the claimed design.
